UNITED STATES PATENT OFFICE.

JAMES A. MOULD, OF MILWAUKEE, WISCONSIN, ASSIGNOR TO EVINRUDE MOTOR COMPANY, OF MILWAUKEE, WISCONSIN, A CORPORATION OF WISCONSIN.

ANTITILTING LOCK FOR REVERSIBLE OUTBOARD MOTORS.

Application filed January 7, 1924. Serial No. 684,719.

This invention relates to improvements in anti-tilting locks for reversible outboard motors.

It is the primary object of this invention to provide a novel, practical, and effective lock mechanism operable to restrain an outboard motor against tilting when the motor is reversed. It is a further incidental object to control both the reversal and the locking 10 of the motor through an adjustment of the tiller handle by means of which the motor is steered.

The motor hereinafter to be described as containing an embodiment of this invention is preferably reversible in the manner invented by Stockemann and disclosed in Letters Patent No. 1,131,287, of March 9, 1915. In other words, the propeller and other submerged parts of the motor are supported by 20 the drive shaft housing and may be released for independent rotation upon a vertical axis for the reversal of the thrust of the motor. It has been customary to accomplish the release of the drive shaft housing 25 and the parts carried thereby for reversing purposes through the medium of a special adjustment of the tiller handle or any hand grip connected therewith so that the operator who is utilizing but one hand to steer the boat, may, with the same hand, and without 30 interference with the steering operation, reverse the motor whenever desired. It is a further very important object of this invention to re-organize the tiller-controlled 35 release of the propeller shaft for reversing purposes to the end that the same tiller movement which accomplishes the reversal of the motor may also operate to lock the motor against tilting.

40 It will be understood that the motor is to be left free to tilt during its normal forward operation so that it may oscillate in a vertical plane if its submerged parts encounter an obstacle. If, however, the motor is reversed, its thrust would then tend to oscillate it if it were not for the provision 45 of the special anti-tilt lock to which this application is particularly directed.

In application, Serial No. 627,664, filed by 50 Herbert J. Hillborn on March 26, 1923, there was disclosed an automatic lock operable upon the partial rotation of the propeller drive shaft about its vertical axis

during reversal. The present invention 55 relates to a positive and direct connection between the tiller handle and a lock for this purpose, such connection being adapted to place the locking operation under the direct control of the operator so that the locking of the motor will actually occur before the reversing operation commences instead of being dependent upon an automatic function performed by the motor when the reversing operation is partially completed. It is a 60 further object of this invention, therefore, to provide in a device of this character for the operation of an anti-tilting lock at the time of commencement of a reversing operation rather than at some later period. 65

The transoms of boats are inclined at various angles so that the brackets which are used for the attachment of outboard motors to small craft ordinarily include rearwardly projecting arms between which there is a block adapted to define the normal vertical 70 position of the motor. In this way the motor can be adjusted about the bracket so that the thrust of its propeller may be directed horizontally to produce a maximum effect in the propulsion of the boat. It is 75 very desirable to have this block not only adjustable but provided with means for fixing its position of adjustment so that when the motor has tilted upon encountering a submerged obstacle and is again restored to 80 its normal position, no readjustment of the positioning block will be necessary. It is proposed, therefore, in connection with the present invention to provide a construction 85 such that the motor will not only be tiltable, 90 and will not only be adapted to be locked against tilting by the operation of the tiller handle, but will also be so designed that after the motor has tilted no further adjustment of the tiller handle and no conscious 95 effort on the part of the operator will be required to restore the motor to the identical upright position from which the tilting operation commenced.

100 Further objects of this invention are to provide a construction for the purposes aforesaid which will be simple, economical of manufacture, easy to operate, and adapted for use with little or no alteration of existing parts and structures; to provide 105 a construction such that it may be operated

similarly to other outboard motor reverses of this general type; to provide a construction in which the tiller will be positively connected to the submerged parts of the 5 motor irrespective of the question as to whether or not the engine is in operation or is exerting any thrust whatsoever through the driving gears in the submerged gear casing so that steering may be accomplished 10 even when the engine is at rest; and to provide a construction in which the operator's hand will be protected from injury when the motor tilts by the release of the tiller from the reversing and locking mechanism for independent pivotal movement.

In the drawings:

Figure 1 is a side elevation of an outboard motor embodying this invention, the showing being largely diagrammatic to indicate 20 the relative positions of the parts, regardless of their relative proportions.

Figure 2 is an enlarged detail view in partial vertical section of the adjustable and normally fixed bearing block, the propeller 25 drive shaft housing, and the lock carried by said housing for co-operation with the bearing block.

Figure 3 is an enlarged detail view taken on the vertical section indicated at 3—3 of 30 Figure 4.

Figure 4 is a horizontal section taken on line 4—4 of Figure 3.

Figure 5 is a detail view on the scale of Figure 1 showing in rear elevation the bearing 35 block illustrated in Figure 1.

Figure 6 is a rear elevation of the co-operating lock member carried by the shaft housing.

Figure 7 is a horizontal section taken on 40 line 7—7 of Figure 1 through the bearing block, the shaft housing, and the locking member.

Figure 18 is a section taken on line 18—18 of Figure 16.

Figure 19 is a detail view in side elevation of the middle plate illustrated in Figure 11.

Figure 20 is a detail view in perspective 75 of a modified bearing block embodying this invention.

Figure 21 is a rear elevation of the complementary interlocking element carried by the shaft housing and adapted for interaction 80 with the bearing block shown in Figure 20.

Figure 22 is a section taken on line 22—22 of Figure 23.

Figure 23 is an assembled view in side elevation of the elements shown in Figures 85 20 and 21, when such elements are in releasing position.

Figure 24 is a view similar to Figure 23 and showing the elements thereof in one position of interlocking engagement.

Figure 25 is a view similar to Figures 23 and 24 and showing the elements in a different interlocking relation.

Like parts are identified by the same reference characters throughout the several views.

Inasmuch as the outboard motor herein disclosed has already been identified as being of the same general type as that disclosed in the patent to Stockemann, No. 1,131,287, of March 9, 1915, it will be unnecessary to describe it in detail. The outboard motor includes an internal combustion engine of which 20 is the crank case, 21 a cylinder, 22 a fly wheel housing and magneto providing current for the operation of spark plugs 105 such as that shown at 23, and 24 is the fuel tank. The crank shaft 26 of said engine is connected with an axially aligned drive shaft 25 by means of a splined connection hereinafter to be described. The drive shaft extends downwardly through a normally vertical shaft housing 28 carrying a submerged gear casing 29 formed to provide rudder elements 30 and 31 and a skeg 32. Within the submerged gear casing 29 the drive shaft 25 is connected with a propeller shaft upon which a nut 34 secures a propeller 35. A suitable pump including a casing shown at 36 forces water through pipe 37 to a duct 38 which is led upwardly within a groove 39 in shaft housing 28 to a distributing chamber 40, from which it is carried by pipe 41 to the cooling jackets of cylinders 21. The water connections are more particularly described in the application of James A. Mould, executed of even date herewith, and entitled "Water supply connections".

The entire outboard motor is pivoted by means of a pin 45 to a bracket 46 having a thumb screw 48 for its attachment to the

- transom of a boat. The bracket is provided with rearwardly projecting arms 49 spaced upon either side of the shaft housing 28. These are the arms already referred to as facilitating the initial adjustment of the motor to a normal upright position from which it is free to tilt during its normal forward operation; but to which it is retained during reversal.
- Bolted to the crank case 20, by means of bolts 50, is a casing element 52 which includes a downwardly extending sleeve 53 having an enlarged portion comprising the water distributing chamber 40. Externally of sleeve 53 is a bearing element 54 apertured at 55 to receive the bracket pivot pin 45. Through this bearing element the entire motor is pivotally connected to the bracket, and within the bearing element the entire motor is free to oscillate upon a vertical axis for steering purposes. Such oscillation for steering purposes is controlled by means of a tiller handle 60 which, although pivotally connected to the motor for movement in a vertical plane, is nevertheless fast thereto for oscillation therewith in a horizontal plane. The particular mounting of the tiller handle 60 will be hereinafter described.
- As previously stated, the crank shaft 26 which is fixed against vertical movement is in splined connection with the drive shaft 25, whereby to permit vertical movement of the drive shaft within the shaft housing 28 and related parts. This splined connection will now be described.
- Threaded or otherwise secured to the lower extremity of drive shaft 26 is a cylinder 61 provided with a bore 62 axially aligned to the crank shaft. The cylinder finds a bearing within a sleeve 63 which is integrally connected with the revolvable portion 64 of a reversing latch mechanism hereinafter to be described. This sleeve 63 is journaled within the interior of sleeve 53 which depends from casing element 52. By this arrangement the drive shaft 25, which fits within bore 52 as illustrated in Figure 3, is given an adequate bearing support at its upper end.
- Extending transversely through the cylindrical member 61 and through the bore 62 thereof is a slot 65 which receives a square key 66 carried by the drive shaft 25. Thus, the crank shaft and the drive shaft are positively connected for simultaneous rotation, although a limited degree of relative vertical movement may occur between them.
- Extending transversely through casing element 52 is a horizontal shaft 68 which is rotatable by the vertical movement of the tiller through mechanism hereinafter to be described. This shaft carries a yoke designated in its entirety by reference character 70 and including a sleeve portion 71 keyed to shaft 68, and a pair of arms 72 and 73 having fingers 74 disposed radially with reference to crank shaft 26. The cylindrical latch element 64 is concentric with the crank shaft and may be provided with a recess 75 adapted to receive a guiding element 76 carried by the crank case 20 and provided with a bushing at 77 for crank shaft 26.
- The latch element 64 is provided with vertically spaced annular flanges 78 and 79 adapted to receive between them the fingers 74 of the yoke or shifting fork 70. Thereby it is made possible for the limited oscillation of shaft 68 to produce a corresponding vertical movement of the latch element 64 and parts connected therewith. The sleeve 63 of latch element 64 is threaded or otherwise connected with shaft housing 28, as indicated at 80, so that when the latch element moves vertically, responsive to the action of shaft 68, the shaft housing 28, submerged gear casing 29, propeller 35, and all related parts will also receive vertical movement. At the same time the arrangement is such that the shaft housing, and latch element 64 are rotatable while supported by the fingers 74 of the yoke or shifting device 70.
- A plate 82 is secured in a relatively fixed position within casing element 52 and adjacent the latch device 64. Plate 82 carries a relatively fixed lug 83 and a resiliently yieldable dog 84 which may project through an aperture in the plate and may be supported by a flat spring 85 in the manner best indicated in Figure 4. The fixed lug 83 and the yieldable dog 84 are spaced apart to receive between them either of a pair of lugs 88 or 89 carried by the latch device 64. Lug 88 is at a higher level than lug 89, but the lugs are preferably substantially opposite to each other across the axis of the drive shaft 26.
- As viewed in plan, the crank shaft and drive shaft of the internal combustion motor illustrated are intended to revolve in a clockwise direction. In transmitting its motion to the propeller shaft through the usual bevel gearing in casing 29 the drive shaft 25 produces a torque tending to rotate the entire casing, propeller, and drive shaft housing bodily about its own axis. When the drive shaft housing is free for such rotation it will actually rotate with its related parts until it is brought to rest by some latch mechanism such as that shown by Stockemann, or such as that which is herein disclosed. There is less resistance to such rotation than there is to the rotation of the propeller. Normally the drive shaft housing and parts connected therewith are maintained against rotation in either direction by the engagement with lugs 88 of the fixed lug 83 on the one side and dog 84 on the other. Thus, there is at all times a positive connection between the tiller and the

propeller irrespective of the existence of the torque above referred to. If, however, the tiller be moved downwardly in a vertical plane to oscillate shaft 68 and the connected 5 yoke or shifting member 70, the result will be to elevate bodily the rotatable latch element 64, shaft housing 28, shaft 25, and all of the submerged parts supported by the shaft housing. As a result of the elevation 10 of these parts, lug 88 on the rotatable latch device will be lifted above the stationary lug 83, and the shaft housing and submerged parts will be free to rotate while supported by the fingers 74. The parts will continue 15 to rotate until lug 89, which is now in the plane of fixed lug 83, acts upon the cam surface of dog 84 to press that dog aside and, passing the dog, engages the fixed lug 83. In this position of the parts the propeller 20 will be removed 180° about the axis of drive shaft 25 from its original position, and consequently, its thrust will be exerted rearwardly. In a broad sense, this reversing operation is considered the equivalent of 25 any other type of reverse. It is, however, accomplished in the distinctive manner above referred to.

The motor will continue to operate in reverse as long as the shaft housing and 30 related parts are maintained in their position of elevation by the depression of the tiller handle. When the tiller handle is elevated, however, the weight of the shaft housing and parts connected therewith will 35 restore the mechanism to the lower level at which the shaft housing and rotatable latch device are indicated in Figure 3. As the downward movement of the rotatable latch device 64 occurs, the lug 89 of said device 40 will pass out of engagement with fixed lug 83, thereby releasing the device and the shaft housing for continued rotation through an additional 180° until lug 88, which has now been restored to the plane of fixed lug 45 83, again contacts with the last mentioned lug. For reasons hereinafter to be pointed out, lug 88 is in a plane slightly vertically removed from the plane of lug 89. The dog 84 serves a dual function in that it absorbs 50 to some degree the shock of the moving parts, and also restrains such parts against retrogressive movement when the torque, productive of clockwise movement, is nonexistent.

55 Means has now been described for accomplishing the reversal of this type of outboard motor in a peculiar manner contemplating the bodily lifting of the propeller to effect its release for bodily rotation to its 60 new position.

The normal upright position of the motor is determined by means of a "block" adjustable between arms 49 of the bracket and 65 designated in its entirety by reference character 90. This block preferably comprises

a channel or semi-tubular portion 91 having a rearwardly extending apertured ear 92 through which a bolt 93 may pass to engage the block adjustably with the bracket. For this purpose the bolt 93 may be inserted 70 through any one of a number of apertures 93' in the bracket arm. The upper end portion 94 of the block is semi-tubular and is concentric with the lower portion 91 thereof but is of greater radius. It is provided 75 with a semi-annular cap 95 having a depending sleeve 96 integrally therewith. These parts are shown in detail in Figures 2, 5, 7, and 8. The block 90 being fastened to the arms 49 of the bracket is, except for its adjustment along said arms, fixed against movement either rotative or vertical with reference to the bracket.

Arranged for co-operation with block 90 is a complementary lock member 98 which may conveniently comprise a sleeve 99 axially slotted at 100 and provided upon either side of said slot with ears 101 through which a clamping bolt 102 may be turned 80 up to flex the wall of the sleeve, and thereby to clamp the device in any desired adjustment along the drive shaft housing 28. At its upper and lower end sleeve 99 carries concentric annular flanges 103 and 104, respectively. These flanges are normally positioned immediately beneath those portion of the block 90 with which they are adapted to co-operate. Flange 103 is spaced from shaft housing 28 at a distance equal to or greater 85 than the thickness of the semi-tubular element 96 carried by the block, and similarly the flange 104 is spaced from sleeve 99 for sufficient distance to be adapted to receive the lower end of the semi-tubular portion 91 of the block. 90

With the parts in the position illustrated in Figure 2 the motor is free to oscillate in a vertical plane about the axis of its pivotal connection at 45, with the bracket. Flanges 103 and 104 are spaced sufficiently below the semi-tubular block elements 96 and 91 to avoid such elements during their bodily oscillation about the axis of pin 45. In the position of the parts indicated in Figure 2 the propeller drive shaft 28 is in its lower 100 position and the motor is operating forwardly. Figures 1 and 3 also illustrate the parts as they appear when the motor is operating forwardly. If, however, the tiller handle 60 is depressed to oscillate the transverse shaft 68 and thereby to elevate shaft housing 28 and related parts, the obvious 105 effect upon the mechanism just described will be to cause the interlocking of flange 103 with the semi-tubular element 96 and the similar interlocking of flange 104 with the lower portion 91 of block 90. The relation of the shaft housing and the lock element 98 carried thereby to the relatively 110 stationary block 90 at the time of reversal 115 120 125 130

is indicated in Figure 8. Obviously, the engagement between flanges 103 and 104 with the semi-tubular elements 96 and 91, respectively, will operate to prevent the motor 5 from tilting about the axis of pin 45, but will have no effect such as to prevent the rotation of the shaft housing for purposes of reversal in the manner already described. As a matter of fact, either of flanges 103 or 10 104, with its complementary portions of block 90, will be adequate to accomplish the desired purpose of locking the motor against tilting. Either may be dispensed with, therefore.

15 By means of the mechanism thus far described, it is obvious that the reversal of the motor is accomplished by the same movement of the tiller handle which adjusts the device to lock the motor against tilting. In 20 a sense the reversal of the motor is automatic since it proceeds after the parts are released for rotation by the adjustment of the shaft housing to a position where it is interlocked with the bracket. Due to the fact that in 25 this particular structure the reversing operation is automatic and is produced by engine torque, it is true that rotation of the housing for the purposes of reversal does not commence until after the housing is 30 interlocked with the bracket. This result is regarded as extremely desirable.

A peculiar consequence of this arrangement is noted when it is desired to restore the motor to forward operation. When the 35 tiller handle is elevated the shaft housing is first caused to drop and, so far as the structure thus far described is concerned, would unlock the motor against tilting before the propeller could swing to a point where its thrust would no longer produce the tilting effect. Therefore, special means 40 is necessary to prevent the anti-tilting lock from becoming disengaged until the reversing operation is so far completed that the thrust of the motor will no longer be exerted in a direction to tilt it. This is accomplished by disposing lugs 89 and 88 in spaced vertical planes, lug 89 being normally sufficiently below the level of the fixed lug 83 45 so that, upon the downward movement of the shaft housing and related parts, lug 89 will be released to permit the rotation of the shaft housing before flanges 103 and 104 are released from interlocking engagement 50 with block 90. To ensure the continuance of this interlocking engagement during the time required for the reversing operation to commence, I provide optionally upon the 55 complementary lock element 98 a small bearing lug 105 which extends slightly beneath flange 103 and is adapted to ride upon the shoulder 106 of the bearing block 90. As 60 long as the tiller handle is maintained in a depressed position so as to support the shaft housing at its full elevation, lug 105 will be

raised out of contact with shoulder 106. When the tiller is released, however, to drop the shaft housing to a position where the lug 89 connected therewith will clear the stationary lug 83, lug 105 of the complementary block member 98 will then contact and ride upon shoulder 106 to support the shaft housing in a position where the flanges 103 and 104 will still be interlocked with block 90 pending the partial completion of the bodily rotation of the propeller. The propeller will at once commence such rotation, due to the fact that lug 89 is free of the stationary lug 83. After it has completed approximately 90 degrees of rotation 80 its thrust will no longer be exerted in a direction to tilt the motor on the bracket, and at that point lug 105 will ride off of shoulder 106 to complete the release of interlocking engagement between members 90 85 and 98.

A modified construction of interlock between the rotatable shaft housing and the bracket is illustrated in Figures 15 to 18, inclusive. The modified construction, like that already described, is adapted to permit the free rotation of the shaft housing with respect to the bracket while interlocking the motor and the bracket to secure it against tilting. Furthermore, in the modified construction the interlocking action is secured by the vertical movement of the shaft housing already described.

The modified block 90' is provided with a bearing wall 126 arcuately formed and concentric with the axis of shaft housing 28. This bearing opens rearwardly to permit the unobstructed rearward passage of the shaft housing when the motor is propelling its boat in a forward direction. The block is provided, however, with oppositely disposed staggered fingers 127, 128, and 129 which may be arranged in the manner indicated in Figures 15 and 16. There is just sufficient clearance between fingers 127 and 129 on the one hand and finger 128 on the other to permit the free passage of the shaft housing. Upon the shaft housing is a bearing element 130 of generally cylindrical contour and arranged to be complementary to the bearing block 90'. Portions of bearing element 130 are cut away as at 131, 132, and 133, such portions corresponding in the normal position of the parts to the fingers 127, 128, and 129, respectively. It will be understood that the bearing element 130 is of sufficient diameter so that it could not pass outwardly between the oppositely projecting fingers of the bearing block if it were not for the provision of the cut away portions just described. By reason of such portions the fingers will not, in the normal position of the parts, interfere with the tilting of the motor.

Intermediate the cut away portions above 130

described are uncut annular portions 134 and 135. A similar annular portion 136 lies beneath the lowest recess 133. The arrangement is such that the upward movement of the shaft housing, produced by the control lever 60, will move the several annular portions 134, 135, and 136 into the plane of fingers 127, 128, and 129, respectively, thereby positively interlocking the motor with the bracket prior to the commencement of the reversing operation. While so interlocked, the complementary bearing element 130 will rotate with the shaft housing within the bearing provided by block 90' and the fingers thereof. The extent of its initial rotation will be 180° and the motor will thereupon be in reverse.

When it is again desired to operate the motor in the forward direction, the pressure upon the tiller handle will be upward to lower the shaft housing and related parts. The intermediate connecting portions 135 and 134 of the bearing element will thereupon move out of the plane of fingers 128 and 127, but the motor will not be released for tilting, due to the fact that in this position of the parts and until the shaft housing has accomplished a partial rotation, the unrecessed portions 137, 138, and 139 of bearing element 130 will lie behind fingers 127, 128, and 129 of the block, respectively. It is only when the shaft housing and bearing element 130 have rotated practically to their original forward positions that recesses 131, 132, and 133 will again be presented to the fingers in such a manner as to free the parts for the tilting of the motor. Consequently, the result of this arrangement is to make unnecessary the use of such a lug as is indicated at 105 in the first described embodiment of this invention.

A third type of interlock between the shaft housing and the bracket is illustrated in Figures 20 to 25, inclusive. In this third type the bearing block 190 is provided with the usual apertured boss 92 through which a bolt may be passed to secure the bearing block between the arms 49 of the bracket. Bearing block 190 is symmetrical in that it is provided on each side with vertically spaced fingers 140. The inner surfaces of such fingers are finished to comprise arcuate extensions of the semi-cylindrical bearing surface provided by the body of the block. The portion of the block intermediate such fingers is semi-circular in cross section and of a diameter adapted to receive freely the complementary interlocking element shown in Figure 21 and hereinafter to be described. Inasmuch as the parts fit accurately together, the under surface of each finger may be beveled, if desired, in the manner best indicated in Figures 23 to 25 inclusive. The bevel is concentric with the pivotal axis about which the motor tilts so that there will

be no binding between the block 190 and the complementary bearing element on the shaft housing.

The device to be mounted on shaft housing 28 comprises a bearing and interlocking element 198 complementary to block 190, and including a sleeve portion 199 which is just sufficiently larger than the shaft housing to be received conveniently thereon, and is provided at spaced intervals, corresponding to the height of fingers 140, with cylindrical portions 142 of increased diameter. Each of the enlarged portions 142 of the sleeve 199 represents a complete circle in plan and each has a bearing surface complementary to that provided by block 190 and the finger extensions thereof. Complementary bearing element 198 may be secured to the shaft housing in any desired manner. For example, it may be co-axial, as at 143, so that the portions of element 198 upon either side of the cut may be sprung together in clamping relation to the shaft housing by means of a countersunk screw 144.

When the parts are properly assembled they will, during the normal operation of the motor, appear as illustrated in Figure 23. The portions 142 of the bearing locking element 198 carried by the shaft housing will be disposed intermediate fingers 140 and will therefore be ineffective to lock the shaft housing to the bracket. When, however, the tiller handle is depressed preparatory to reversing the motor, shaft housing 28 will be elevated in the manner described and, by reason of the vertical movement of the shaft housing, each of the enlarged cylindrical bearing elements 142 will be raised into the plane of a finger carried by block 190. As soon as the annuli 142 are engaged behind their respective finger portions of block 190, the motor will be locked against tilting and the reversing operation may commence.

In the ultimate position reached by the tiller handle the parts will appear as they are shown in Figure 25. It will be noted that each of the cylindrically surfaced annuli 142 is vertically aligned within the grasp of a pair of oppositely disposed fingers upon block 190. A large amount of bearing surface is thereby provided so that the friction developed during the reversing operation will not produce abnormal wear between the interlocking parts.

As previously stated, when it is desired to permit the continued rotation of the shaft housing to restore the motor for forward propulsion, the first operation consists in releasing the automatic reversing mechanism to permit of the free rotation of the shaft housing. The parts are so arranged that when the tiller is elevated sufficiently to release the shaft housing for rotation the cylindrically surfaced members 142 will still

be interlocked with fingers 140 to substantially the extent indicated in Figure 24. In other words, the parts will not yet be free for tilting. If desired, the motor may be operated with the parts thus locked against tilting.

If, however, the upward movement of the tiller be continued subsequently to the time when the shaft housing and propeller reach their normal positions for forward propulsion, the parts will again reach the relative positions indicated in Figure 23, so that the motor will be freed for tilting.

Three different types of interlocking mechanism for securing the motor against undesired tilting with respect to the bracket have thus far been described. In each case the interlocking of the motor and bracket is manually controlled and occurs immediately upon the depression of handle 60. In each case the reversing operation is automatic and occurs subsequently to the interlocking of the motor and bracket. In each case also the restoration of the shaft housing and propeller to normal forward driving position occurs before the interlock between the motor and bracket is released.

It is somewhat of a problem to connect pump casing 36 with the water jacket of cylinders 21 while permitting relative rotative and vertical movement between the pump and the water jacket. This is preferably accomplished, however, in a way which is described more particularly in the co-pending application executed of even date herewith by me, James A. Mould, and entitled "Water supply connections". Briefly stated, the desired result is accomplished by longitudinally grooving the shaft housing 28 in the manner indicated at 39 so that the tube 38, connected with pipe 37 and extending upwardly in groove 39, is entirely within the radius of the shaft housing. So located, the tube is protected from all injury and is at the same time readily accessible. At its upper end this tube discharges into the distributing chamber 40 which has upper and lower packing rings adapted to prevent leakage at this point. The chamber is adapted to receive water from tube 38 irrespective of the position of rotation of shaft 28, and the water so received is led from the chamber to pipe 31. The vertical height of the chamber is sufficient so that irrespective of the vertical movement of shaft housing 28 and related parts water delivered from tube 38 will always be received into the chamber.

When an outboard motor is tilted accidentally, due to encountering a submerged obstacle in the water, a serious injury to the hand of the operator is likely to result if the tiller is made fast to the motor so as to tend to force the hand of the operator downwardly against the seat of the boat.

Consequently, various patentees have made provision to permit the handle to yield upwardly with reference to the motor. Ordinarily, however, where such provision has been made the tiller has performed no function other than that of directing the course of the craft to which the motor is attached. In the present case the tiller not only directs the course of the boat but also, when depressed, serves to lock the motor against tilting and to put it in condition for automatic reversal. Consequently, it is desirable to make some provision for releasing the tiller for free upward movement with respect to those parts which it controls. In a degree this might be accomplished by an ordinary stop hinge adapted to leave the tiller handle free to yield upwardly while permitting its downward movement to be transmitted to the rock shaft 68 for the control of the locking and reversing operations. If such a hinge is used, however, the motor would be out of the operator's control and serious consequences of encountering a submerged obstacle might be made even more serious than as if the motor were of the non-tilting variety. It will be remembered that the reversal of this motor is accomplished by lifting the drive shaft and the submerged portions of the motor. Consequently, it will be obvious that if the submerged obstacle acted upon skeg 32 in a way to lift these parts, the motor might automatically reverse itself and again run upon the obstacle. At best, the motor would be temporarily out of control and the shaft housing would be free of any restraining influence and could move upwardly or downwardly subject to all forces acting thereon.

To guard against such a contingency, I have devised an appliance through which the tiller handle is connected with rock shaft 68, and which is so constructed that in the normal position of tiller handle, and in any elevated position thereof with respect to the remainder of the motor, the shaft housing and all related parts will be locked against vertical movement and will be released for vertical movement only when the tiller handle is actually depressed by the operator.

The safety appliance for securing the reversing and anti-tilt lock against accidental operation is disclosed in Figures 11 to 14, inclusive. It comprises a series of three plates 110, 111, and 112. Plate 110 may conveniently comprise a part of the crank case casting, if desired. If it is a separate element it is screwed to the casting by screws inserted in the apertures 113. Each of the three plates 110, 111, and 112 is provided with an opening adapted to receive a sleeve 114, which is shown in dotted lines in Figure 4, and to which sleeve the plate 111 is keyed. The sleeve in turn is keyed to transverse shaft 68 which extends outwardly

from casing element 52 for that purpose. Thereby the movements of plate 111 are made to control the movements of the shaft housing for reversing purposes, and for interlocking the motor with the bracket. Plate 112 carries the tiller, being provided with a boss at 114' having a socket at 115 for that purpose. Means now to be described connects plate 111 normally with the 10 relatively fixed plate 110 and connects plate 111 with plate 112 as soon as plate 112 is actuated by a downwardly depression of the tiller handle.

Plate 111 is provided with an opening 117 which extends therethrough from one side to the other. Each of plates 110 and 112 are provided with recesses indicated respectively at 118 and 119. A steel ball 120, similar to those used in ball bearing, is 20 disposed in hole 117 and is of greater diameter than the thickness of plate 111 so that the ball 120 will necessarily project from said hole at one side or both sides of plate 111. A stop 319 projecting forwardly from 25 plate 110 is adapted to contact with a pin 320 projecting at both sides of plate 111. When the pin contacts with the stop, the recess 118 will be aligned with hole 117 in the manner indicated in Figure 12. Plate 30 112 is provided with a similar stop at 121 which, during the normal steering of the craft, will usually be slightly above pin 320 or may contact therewith. When stop 121 contacts with pin 320, recess 119 will be 35 aligned with hole 117. The normal position of the recess, however, will be slightly out of the line with said hole and above said hole, as indicated in Figure 12. Thereby the ball 120 will tend to project from 40 hole 117 into recess 118 and, if the tiller is moved upwardly relative to the motor, as by the tilting of the motor when an obstacle is encountered, then the imperforate surface of plate 112 will positively confine the ball in a position wherein it will be partially 45 within the hole 117 and partially within recess 118. In the normal positions the ball will tend to be so confined, due to the fact as aforesaid, that recess 119 will in normal 50 position of the parts be slightly elevated above hole 117. Obviously, when the ball is confined as aforesaid, to be partially in plate 110 and partially in plate 111, the result will be to key these plates together 55 against relative movement in either direction, and since plate 111 is keyed to the rock shaft 68 which controls the reversal of the motor and its interlocking with the bracket, there can obviously be no adjustment of the 60 motor for reversal or interlocking as long as the ball retains this position. Thus, whenever the motor is tilted and the tiller is retained in the hand of the operator, no reversal or interlocking of the motor and bracket can occur.

When, however, the tiller is depressed, as in the conscious attempt of the operator to reverse the motor, plate 112 will be oscillated slightly downwardly until its stop member 121 contacts with pin 120. This 7 initial movement of plate 112 will bring its recess 119 into alignment with hole 117. Thereafter, due to the contact of stop 121 with pin 320, the plate 111 will commence to move downwardly with the tiller. The 7 relative movement occurring between plates 111 and 110 will cause recess 118 to move out of alignment with hole 117, and the ball 120 will thereby be forced across hole 117 into the recess 119 which is aligned therewith. In consequence of such movement, the ball will key plate 111 to plate 112 so that the tiller will be enabled to oscillate rock shaft 68 and thereby to interlock the 8 motor with the bracket and to free the parts 81 for reversal. Figure 13 illustrates the relation of recesses 118 and 119 to hole 117 during reversal. Due to the fact that plates 111 and 112 are keyed together by ball 120 the pin 320 is not called upon to withstand 91 the strain of lifting the shaft housing and related parts.

The plates may be made to perform a further function of defining certain positions of the tiller handle, if desired. For 91 this purpose a hole 145 may be bored in block 110 and may extend therethrough into the casing member 52. A spring may be seated in this hole to press outwardly a 10 ball 146.

In the opposing face of plate 111 will be a series of depressions 148, 149, and 150, one of which appears in Figure 9, and all of which are shown in Figure 19. In the normal position of the tiller handle, to wit,— in its elevated position when the shaft housing is fully depressed and the motor is free to tilt, the interlocking parts being disposed as illustrated in Figures 2, 15, and 23, the recess 150 in the face of plate 111 will register with hole 145 in plate 110, and the ball 146 will be forced by the spring behind it into the registering recess. To displace the ball and permit relative movement to occur between plates 110 and 111 will require a certain degree of downward pressure upon the tiller handle, and therefore, the location of recess 150 will define a tiller handle position in which the motor will be disposed for forward propulsion and will be free to 11 tilt.

Similarly, recess 148 will, in the extreme depressed position of the tiller handle, register with hole 145 and receive the ball. In this position of the tiller handle the shaft housing and propeller will necessarily have rotated to their reverse positions, and the degree of interlock between the shaft housing and the bracket will necessarily be full. The relation of the interlocking elements in 12 13

this position of the tiller handle is illustrated in Figures 16 and 25. Intermediate recess 149 may be used similarly to indicate an intermediate position of the tiller in which the interlocking elements are in the relative positions illustrated in Figures 8 and 24. This definition of the intermediate tiller position is particularly useful in connection with the third type of interlock hereinbefore described.

From the foregoing it will be understood that a motor constructed in accordance with the disclosure herein will safeguard the operator in every particular, and will nevertheless be subject to operation along the usual lines and may be constructed, quite cheaply, with standard parts. The motor will be steered by the oscillation of tiller 60 in a horizontal plane. As previously stated, for steering purposes the whole device, including the engine, oscillates within the bearing member 54 which connects the motor proper with the bracket. The block 90, which controls the normal upright position of the motor, is designed to permit the motor to oscillate on a vertical axis for steering purposes, and for that purpose is provided with an arcuate bearing surface concentric with the axis of the drive shaft 25 and shaft housing 28. It is not contemplated that the block 90 will be moved after having been adjusted to compensate for the angle of the transom of any given boat. During the normal forward operation of the motor the motor is not interlocked with block 90 but is held thereagainst solely by the thrust of propeller 35 which, being exerted in a forward direction, tends to force the shaft housing into the arcuate semi-circular bearing provided by the block. When the motor tilts, its initial movement will lock it against reversal, and, after the obstacle has passed, the continued forward thrust of the propeller will restore the motor to its normal upright position in contact with the block. Under no circumstances is any adjustment necessary to restore the motor to normal position after it has been tilted.

On the other hand, when the tiller handle is depressed to lock the motor against tilting, reversal will immediately follow, being automatically accomplished in a manner consequent upon the particular method of interlocking the motor with the bracket. The motor cannot operate in reverse without being interlocked with the bracket as aforesaid, and the motor cannot operate in a forward direction without being free to tilt. This is true, irrespective of the extent to which the motor is oscillated bodily for steering purposes.

While the advantages of the particular arrangement herein disclosed will be apparent from the foregoing discussion, I wish nevertheless to make it clear that, broadly

speaking, many other types of reversing mechanisms may be employed in conjunction with locking devices to be operated by the tiller of an outboard motor, and to accomplish results similar to those accomplished with the particular construction herein disclosed. Various other types of interlocks may also be employed to secure the motor against tilting and to secure results similar to those contemplated in the use of the particular construction herein illustrated. It is also possible to design other devices within the scope of this invention for locking the controls when the tiller handle is in its normal position or is elevated with respect to the motor. Furthermore, I recognize the fact that it would not change the principle of operation hereof to use a grip device on the tiller handle to perform some one or more of the functions which are controlled in the present embodiment of my invention by the tiller handle itself.

I claim:

1. In a device of the character described, the combination with a bracket and an outboard motor pivotally connected therewith for tilting movement and provided with a normally upright drive shaft, of a sleeve encircling said drive shaft and provided with an arcuate lock element substantially concentric with said sleeve, and a supplementary arcuate lock element connected with said bracket and normally out of engagement with said first mentioned lock element, said arcuate elements being adapted for interlocking interaction upon the occurrence of relative axial movement between said elements in a given direction, whereby said outboard motor may be secured against pivotal movement.

2. In a device of the character described, the combination with a bracket and an outboard motor pivotally connected therewith for tilting movement and provided with a normally upright drive shaft, of a sleeve encircling said drive shaft and provided with an arcuate lock element substantially concentric with said sleeve, and a supplementary lock element connected with said bracket and provided with an arcuate portion normally out of engagement with said first mentioned lock element and adapted for interlocking interaction therewith upon the occurrence of relative axial movement between said elements in a given direction, together with a tiller handle operatively connected with said motor to control the direction of thrust thereof, said tiller having a portion mounted for independent pivotal movement other than that required for the direction of said motor, and being operatively connected with one of said lock elements for the transmission thereto of said pivotal movement of said tiller portion in a direction to produce relative axial

movement between said element to effect their interlocking engagement.

3. In a device of the character described, the combination with a bracket and an out-board motor pivotally supported thereby and having a normally upright shaft, of a housing for said shaft and movable vertically along the axis of said shaft, said housing being also rotatable about said axis, 5 catch mechanism engageable with the housing in either of its extreme positions of vertical movement and upon 180° of rotation thereof, lock mechanism associated with said housing and engageable with said bracket upon movement of the housing vertically upwardly, and manually controllable means for moving said housing vertically upward.

4. In a device of the character described, 20 the combination with a bracket and an out-board motor pivotally supported thereby and having a normally upright shaft, of a prime mover rotatable by and movable about said shaft, latch mechanism and lock mechanism simultaneously operable to permit the movement of said prime mover about said shaft through an arc of 180° and to prevent pivotal movement of said motor, 25 said latch mechanism and lock mechanism each including a non-rotatable member and a member rotatable about the axis of said shaft and connected with said prime mover, said members being movable relatively vertically to effect the operation of said latch 30 and lock mechanism, and manually operable means for effecting relatively vertical movement between said members.

5. In a device of the character described, 40 the combination with a bracket and an out-board motor pivotally connected therewith, and having a prime mover portion said bracket and motor being formed for abutment in an upright position of said motor, whereby to define a position for said motor 45 to which said motor can return without manipulation after pivotal movement with reference to said bracket, and said motor being normally freely movable to said abutment about its pivotal connection with said bracket, a manually operable interlocking device for securing said motor against tilting movement with said bracket, and reversing mechanism operative to control the direction of propulsion of said motor, with 50 reference to the prime mover portion thereof said mechanism being operatively connected with said interlocking device for control therewith to reverse said motor upon the completion of the interlocking of said 55 motor with said bracket.

6. In a device of the character described, 60 the combination with a bracket and an out-board motor pivotally connected therewith and including a prime mover and propulsion mechanism, a support for said pro-

pulsion mechanism rotatably adjustable with reference to said prime mover, and a latch manually operable to release said support for predetermined degrees of automatic reversal subject to the torque of said prime 70 mover, of interengageable lock parts carried respectively by said bracket and said support and adapted for engagement and disengagement upon the occurrence of vertical movement of one of said parts with 75 reference to the other, and motion transmitting connections operative to control said latch and connecting it with the movable part, said connections being adapted to operate said latch to release said support for 80 automatic reversal upon the completion of the interlocking of said parts whereby to secure said motor against pivotal movement with reference to said bracket.

7. In a device of the character described, 85 the combination with a bracket and a dirigible outboard motor pivotally connected therewith for tilting and provided with a manually operable lever for the control of the direction of operation of said motor, 90 said lever having a pivotally movable portion, of a stop carried by said bracket and adapted to define the normal upright position for said motor, said motor being normally freely movable to and from said stop, 95 and a lock device connected with said lever portion for control by the pivotal movement thereof irrespective of the steering position of said motor and adapted for the interlocking engagement of a portion of said motor 100 with a portion of said bracket.

8. In a device of the character described, the combination with a bracket and an out-board motor pivotally connected therewith for tilting movement, of a stop lock adjustable with reference to said bracket and providing an open sided bearing to receive thrust from a portion of said motor, a lever carried by said motor and operatively connected for manual operation to control the 105 direction of operation of said motor, and a latch device including elements carried by said motor and said block, one of said elements being mounted for vertical movement and connected with said lever to be controlled thereby for the operative interlock and release of said motor and said bracket.

9. In a device of the character described, 110 the combination with a bracket and an out-board motor pivotally connected therewith for tilting movement, of a stop block connected with said bracket and providing an open sided bearing to receive thrust from a portion of said motor, a tiller lever connected with said motor and adapted to control the direction of propulsion of a boat 115 to which said bracket is attached, and a latch device including relatively vertically movable, engageable parts, one of said parts being connected with said motor and another 120

of said parts being connected with said bracket, said device being operatively connected with said lever for manual control thereby.

5. 10. In a device of the character described, the combination with a bracket and a dirigible outboard motor pivotally connected therewith for tilting movement and provided with a prime mover portion and reversing mechanism, adapted to reverse its direction of thrust relative to said portion of a steering lever operatively connected to control said reversing mechanism, and a latch device including relatively movable 15 elements connected respectively with said motor and with said bracket, one of said elements being connected operatively with said lever to be controlled thereby and mounted for vertical adjustment subject to 20 such control with reference to said prime mover portion.

11. In a device of the character described, the combination with a bracket, of a motor tiltably and rotatably mounted with respect thereto and including a tiller lever adapted to be grasped by an operator to control the rotative position of said motor, of a latch device including relatively movable complementary elements connected respectively with said bracket and with said motor, said tiller lever being pivotally operative independently of motor rotation to produce relative movement between said elements, whereby to control manually the operation of said latch device.

12. In a device of the character described, the combination with a bracket and an outboard motor pivotally and rotatably connected with said bracket for tilting and directional movement, of a latch device including a pair of complementary elements adapted for relative rotative and axial movement, said elements being connected respectively with said bracket and with said motor, and a manually operable lever connected with one of said elements and adapted to produce relative axial movements between said elements, such movements being productive of interlocking engagement and 50 release of said elements.

13. In a device of the character described, the combination with a bracket, of an outboard motor pivotally connected therewith and including reversing mechanism, a lever including a portion normally projecting substantially horizontally from said motor, means for connecting said lever portion operatively with said reversing mechanism for the control thereof in depressed positions of said portion, and means for disconnecting said portion from said mechanism when said portion is elevated above its normal position.

14. In a device of the character described, 65 the combination with a bracket, of an out-

board motor tiltably connected therewith and including reversing mechanism, a manually operable lever normally disposed in a predetermined position and connected with said reversing mechanism and including a portion free to move in one direction from said position without affecting said mechanism, and a key controlled by the free movement of said lever portion and adapted to lock said mechanism against operation when 75 said lever portion is in motion without affecting said mechanism.

15. In a device of the character described, the combination with the reversing mechanism of an outboard motor, of a manually operable lever including first and second parts independently mounted, a relatively stationary member adjacent said first part, a key adapted to engage said first part alternatively with said member and with the 80 said second part, and means operatively connecting said first part with said reversing mechanism for the control thereof, whereby said first and second parts, when engaged by said key, may be moved simultaneously 85 for the control of said reversing mechanism, and whereby said second part may be moved independently of said first part, said first part being keyed to said member with said reversing mechanism secured inoperative 90 thereby.

16. In a device of the character described, the combination of a pair of members pivotally mounted for movement about a common axis, one of said members being manually operable and the other being attached to motion transmitting connections, of a stationary part adjacent said other member, and a key reciprocable through said other member and engageable alternatively with 105 said part and the manually operable member.

17. In a device of the character described, the combination of a pair of members pivotally mounted for movement about a common axis, one of said members being manually operable and the other being attached to motion transmitting connections, of a stationary part adjacent said other member, 110 a key reciprocable through said other member and engageable alternatively with said part and the manually operable member, and means for rendering the shifting of said key automatically responsive to movements of said members, whereby in certain 115 positions of said manually operable member said other member will be locked thereto and in other positions of said manually operable member said other member will be locked to said part.

18. In a device of the character described, the combination with a relatively stationary member of an internal combustion engine, of a plate oscillatory adjacent said member and provided with a transverse hole at a 120 125

- point remote from its axis of oscillation, a second plate oscillatory co-axially with the first plate and provided with a recess radially equi-distant with said hole from the axis of oscillation of said plates and adapted in one position of said first plate for registry with said hole, and a key reciprocable in said hole and having greater transverse extent than said hole, said key being receivable in a recess in registry with said hole, whereby said key is adapted to engage said first plate alternatively with either said member or said second plate.
19. In a device of the character described, the combination with a relatively stationary member of an internal combustion engine, of a plate oscillatory adjacent said member and provided with a transverse hole at a point remote from its axis of oscillation, a second plate oscillatory co-axially with the first plate and provided with a recess radially equi-distant with said hole from the axis of oscillation of said plates and adapted in one position of said first plate for registry with said hole, a key reciprocable in said hole and having greater transverse extent than said hole, said key being receivable in a recess in registry with said hole, whereby said key is adapted to engage said first plate alternatively with either said member or said second plate, and means limiting the independent movement in one direction of said first plate with respect to said member and to said second plate.
20. In a device of the character described, the combination with an outboard motor provided with reversing mechanism and a relatively stationary member having a recess and a shoulder, of a first plate oscillatory about a given axis and adjacent said member, said first plate being operatively connected with said reversing mechanism for the control thereof and being provided with a hole radially equi-distant with said recess from the axis of oscillation of said plate, a second plate mounted for oscillation co-axially with said first plate and provided with a recess radially equi-distant with said hole from said axis and also provided with a shoulder radially equi-distant with the shoulder of said member from said axis, a transverse pin carried by said first plate and projecting for operative engagement alternatively with the shoulders of said member or said second plate, and a key comprising a ball reciprocable in said hole and having a diameter greater than the length of said hole and less than the combined length of said hole and one of said recesses, said second plate being manually operable.
21. In a device of the character described, the combination with a relatively stationary part, and a tiltable motor unit including a vertically movable member, of interlockable elements carried by said part and said mem-
- ber and adapted for engagement and release upon the vertical movement of said member, said part being adjustable to comprise a stop for defining a normal upright position for said unit.
22. In a device of the character described, the combination with a bracket, of an outboard motor pivotally connected therewith and including a propeller, and a propeller supporting member bodily reciprocable vertically, said support being formed for engagement with a portion of said bracket upon its vertical reciprocation.
23. In a device of the character described, the combination with a bracket, of an outboard motor pivotally connected therewith and including an engine and propeller, and a support normally connecting said propeller with said engine, said support being guided for rotative movement with respect to said engine and for vertical movement with respect to said bracket, and said support and said engine being provided with an interlock releasable upon the vertical movement of said support for permitting rotation of said support, and said support and said bracket being provided with an interlock engageable upon the vertical movement of said support for preventing tilting movement of said motor.
24. In a device of the character described, the combination with the relatively stationary member of an outboard motor, of a propeller support rotatable with respect to said member and provided with diametrically opposite lugs at differing levels, a lug relatively fixed against rotation and disposed in the path of rotative movement of the lugs carried by said support, and means for producing relative vertical movement of said lugs, whereby said relatively fixed lug may be disposed alternatively at the level of either of said diametrically opposite lugs.
25. In a device of the character described, the combination with the relatively stationary member of an outboard motor, of a propeller support rotatable with respect to said member and provided with diametrically opposite lugs at differing levels, a lug relatively fixed against rotation and disposed in the path of rotative movement of the lugs carried by said support, means for producing relative vertical movement of said lugs, whereby said relatively fixed lug may be disposed alternatively at the level of either of said diametrically opposite lugs, and a pawl spaced from said relatively fixed lug and resiliently yieldable from the path of movement of the lugs of said support, said pawl being adapted to co-operate with said relatively fixed lug to prevent movement in either rotative direction of a rotatable lug engaged with the fixed lug.
26. In a device of the character described, the combination with a rotatable propeller

- support provided with diametrically opposite lugs at different levels, of a relatively fixed stop disposed in the rotative path of movement of said lugs and adapted to engage a lug at the level thereof, said support being vertically adjustable to bring either of the lugs carried thereby alternatively into the horizontal plane of said stop.
27. In an outboard motor, the combination with a relatively stationary member, of a propeller support rotatably and axially slidably journaled therein, a crank shaft rotatable with respect to said member, a drive shaft aligned with said crank shaft and journaled in said support for axial movement therewith, and a splined connection between said crank shaft and said drive shaft and adapted to connect said shafts for simultaneous rotation while permitting relative axial movement.
28. In a device of the character described, the combination with a rotatable, vertically movable propeller support having a portion provided with a peripheral groove, of a shipper operatively engaged with said groove to control the vertical movement of said support while permitting the free rotation thereof, a plurality of lugs radially projecting from said support at different levels and at like radial distances from the axis of rotation of said support, and a relatively fixed stop equidistant with said lugs from the axis of rotation of said support, said lugs being selectively engageable with said stop upon the axial movement of said support, whereby a given lug is brought to the plane of said stop.
29. In a device of the character described, the combination with a rotatable support, of a plurality of lugs projecting radially from said support and having portions in different planes normal to the axis of rotation of said support, said lugs being equi-distant radially from said axis of rotation, and a stop relatively fixed against rotation about said axis and equi-distant with said lugs therefrom, said motor being constructed to provide for relative movement in the direction of the axis of said support between said stop and said support, whereby said stop may be selectively engaged with said lugs.
30. In a device of the character described, the combination with a bracket, of an outboard motor pivotally connected with said bracket and including a propeller support rotatably and axially movable with respect to said bracket, radially projecting lugs equi-distant from the axis of rotation of said support and spaced along said axis in different horizontal planes, a relatively fixed stop disposed in the path of rotative movement of said lugs and selectively engageable with either upon the vertical movement of said support, whereby the position of said support in its path of vertical movement will be determinative of its rotative position through the engagement of one or the other of said lugs with said stop, and means operative upon the vertical movement of said support for engaging said support with said bracket to lock said motor against pivotal movement with respect to the bracket.
31. In a device of the character described, the combination with a bracket, of an outboard motor pivotally connected therewith for tilting movement and including a rotatably and vertically movable upright propeller support, latch mechanism engageable with said support in one position of vertical movement thereof to define a given rotative position therefor and operative in a different position of vertical movement of said support to define a different rotative position therefor, and an interlock between said support and said bracket comprising a rearwardly opening bearing block connected with said bracket and provided with a bearing surface concentric with the axis of rotation of said support and of greater diameter than said support, said surface being formed to permit the tilting movement of said motor, and a complementary bearing element carried by said support and adapted for interlocking engagement with said block upon the upward axial movement of said support.
32. In a device of the character described, the combination with an outboard motor casing and a sleeve depending therefrom and rotatably adapted to support a propeller for forward or rearward propulsion, a vertically movable member provided with a radial lug and connected with said sleeve to control the rotative position thereof, and a stationary lug engageable with the lug of said member in one position of vertical adjustment of said member to define a given position of rotative adjustment of said sleeve.
33. In a device of the character described, the combination of a sleeve supported for rotation on its axis and a propeller directed laterally of said sleeve and adapted to be controlled directionally by the rotation of said sleeve on its axis, of a vertically movable member connected with said sleeve to control its rotative position, and means for controlling the rotative position of said sleeve in conformity with the vertical movement of said member, whereby in a plurality of given positions of vertical adjustment of said member said sleeve will occupy a plurality of predetermined positions of rotative adjustment.
34. In a device of the character described, the combination with a support for the submersible portions of an outboard motor, said support being mounted for vertical and rotative movement, of means operable upon the vertical movement of said support to produce rotation thereof, and stops adapted to limit the rotation of said support, said stops

- being adapted to define predetermined positions in the rotation of said support corresponding to predetermined positions of vertical movement thereof.
5. 35. In a device of the character described, the combination with a bracket and a motor pivoted for tilting movement with respect thereto, and including a normally upright shaft and a housing for such shaft, of concentric interlockable parts carried respectively by said housing and said bracket and adapted for engagement upon the occurrence of relative movement axially of said shaft, together with means for producing such movement for the engagement and disengagement of such parts.
10. 36. In a device of the character described, the combination with a bracket and a motor pivoted for tilting movement with respect thereto, and including a normally upright shaft and a housing for such shaft, of concentric interlockable parts carried respectively by said housing and said bracket and adapted for engagement upon the occurrence of relative movement axially of said shaft, together with means for producing such movement for the engagement and disengagement of such parts, the parts connected with the bracket being formed to provide an open sided bearing with reference to which said housing is rotatable and to and from which said motor is freely oscillatable when said parts are not in engagement.
15. 37. In a device of the character described, the combination with a bracket, of an outboard motor pivotally connected therewith and including a vertically adjustable propeller support rotatable from a given position upon vertical movement from a given position, and means for interlocking said support with said bracket upon the occurrence of said vertical movement.
20. 38. In a device of the character described, the combination with a bracket of an outboard motor pivotally connected therewith and provided with a drive shaft, a sleeve substantially concentric with said drive shaft and rotatably and vertically adjustable, a lock element carried by said sleeve and provided with a bearing surface concentric with the axis of said shaft, a complementary lock element connected with said bracket, said elements being engageable upon the vertical movement of said sleeve, a relatively fixed part and a latch member connected with said sleeve and normally engaged with said part, said member being releasable from said part upon the vertical movement of said sleeve.
25. 39. In a device of the character described, a shaft housing rotatable for reversing purposes, a stop adapted to limit the rotative movement of said housing, said housing being provided with a member formed for engagement with said stop, and resiliently yieldable means disposed adjacent said stop and adapted to cushion the contact of said member with said stop.
30. 40. In a device of the character described, a shaft housing rotatable for reversing purposes, a stop adapted to limit the rotative movement of said housing, said housing being provided with a member formed for engagement with said stop, and resiliently yieldable means disposed adjacent said stop and adapted to cushion the contact of said member with said stop, said means comprising a dog formed with a cam face and adapted to be pressed aside by said member and to confine said member against the stop.
35. 41. In a device of the character described, the combination with a bracket and an outboard motor pivotally connected to said bracket for tilting, said outboard motor including a prime mover, propulsion mechanism, and a support carrying said propulsion mechanism and adapted for reversal with respect to said prime mover and for vertical adjustment with respect thereto, latch mechanism adapted in one position of said support to secure it against reversal with respect to said prime mover, and in a different vertical movement of said support to release said support for reversal, and arcuate interlocking parts mounted concentrically upon the bracket and support respectively and normally disengaged when said support is held by said latch mechanism against reversal, said parts being positioned for interengagement when said support is adjusted vertically to the position for reversal.
40. 42. In a device of the character described, the combination with a bracket and an outboard motor pivotally connected to said bracket for tilting, said outboard motor including a prime mover, propulsion mechanism, and a support carrying said propulsion mechanism and adapted for reversal with respect to said prime mover and for vertical adjustment with respect thereto, latch mechanism adapted in one position of said support to secure it against reversal with respect to said prime mover, and in a different vertical movement of said support to release said support for reversal, and arcuate interlocking parts mounted concentrically upon the bracket and support respectively and normally disengaged when said support is held by said latch mechanism against reversal, said parts being positioned for interengagement when said support is adjusted vertically to the position for reversal, together with a tiller handle for said motor mounted for a steering movement and a secondary movement and provided with connections adapted to transmit such secondary movement to said support to produce vertical adjustment thereof.
45. 43. In a device of the character described,

the combination with a bracket and an out-board motor in pivotal connection therewith and including a support for submersible parts of said motor, of substantially concentric lock devices mounted respectively on said bracket and support and adapted for engagement and disengagement upon the occurrence of relative axial movement between said devices, said devices being formed to permit of the rotation of said support with respect to said bracket when engaged and to secure said motor against pivotal movement with respect to said bracket when so engaged, together with a handle connected with one of said devices and adapted to adjust said devices in a direction for engagement and disengagement of said devices.

JAMES A. MOULD.
